UNITED STATES PATENT OFFICE.

ELMER E. STOCKTON, OF BRISTOL, CONNECTICUT, ASSIGNOR TO THE E. INGRAHAM CO., OF BRISTOL, CONNECTICUT, A CORPORATION.

DESIGN FOR A RING-HEAD FOR ALARM-CLOCKS.

42,983.

Specification for Design.

Patented Sept. 3, 1912.

Application filed April 6, 1912. Serial No. 689,084. Term of patent 7 years.

To all whom it may concern:

Be it known that I, ELMER E. STOCKTON, a citizen of the United States, residing at Bristol, in the county of Hartford and State of Connecticut, have invented a new, original, and ornamental Design for a Ring-Head for Alarm-Clocks; and I do hereby declare the accompanying drawing to be a full, clear, and exact illustration of the same, and which said drawing constitutes part

of this application and represents a face view of a ring-head for alarm-clocks embodying my design.

I claim:

The ornamental design for a ring-head for alarm clocks as shown.

ELMER E. STOCKTON.

Witnesses:

Wm. P. HYNDS,
H. W. BENNETT.
